(57) **CLAIM**

The ornamental design for a straw container as shown and described.

DESCRIPTION

FIG. 1 is a top perspective view of a straw container. FIG. 2 is a bottom perspective view of the straw container of FIG. 1.

FIG. 3 is a front view of the straw container of FIG. 1.

FIG. 4 is a back view of the straw container of FIG. 1.

FIG. 5 is a right side view of the straw container of FIG. 1.

FIG. 6 is a left side view of the straw container of FIG. 1.

FIG. 7 is a top view of the straw container of FIG. 1.

FIG. 8 is a bottom view of the straw container of FIG. 1.

FIG. 9 is an exploded top perspective view of the straw container of FIG. 1, depicting an environment; and,

FIG. 10 is an enlarged partial perspective view of the straw container of FIG. 1.

The broken lines depict an environment of the straw container that form no part of the claimed design.

1 Claim, 9 Drawing Sheets
